Primary Examiner — Cynthia Ramirez*(74) Attorney, Agent, or Firm* — Polson Intellectual Property Law, PC; Margaret Polson(57) CLAIM

The ornamental design for a cart, as shown and described.

DESCRIPTION

FIG. 1 is a front side isometric view of our new design for a cart.

FIG. 2 is a left side elevation view of FIG. 1.

FIG. 3 is a right side elevation view of FIG. 1.

FIG. 4 is a front side elevation view of FIG. 1.

FIG. 5 is a back side elevation view of FIG. 1.

FIG. 6 is a bottom plan view of FIG. 1.

FIG. 7 is a top plan view of FIG. 1; and,

FIG. 8 is a back side isometric view of FIG. 1.

The features shown in light grey in the drawings depict unclaimed subject matter and unclaimed borders only and form no part of the claimed design.

1 Claim, 8 Drawing Sheets(56)
